(57) **CLAIM**

The ornamental design for a “locating ring,” as shown and described.

DESCRIPTION

FIG. 1 is a bottom, front, and left side perspective view showing my new design for a locating ring.

FIG. 2 is a front plan view of the locating ring shown in FIG. 1.

FIG. 3 is a left side view of the locating ring shown in FIG. 1, the right side view being a mirror image thereof.

FIG. 4 is a bottom view of the locating ring shown in FIG. 1, the top view being a mirror image thereof; and,

FIG. 5 is a rear plan view of the locating ring shown in FIG. 1.

The subject matter shown in dashed lines is for illustrative purposes and forms no part of the claimed design.
